UNITED STATES PATENT OFFICE.

FREDERICK W. HUNT, OF PASADENA, CALIFORNIA.

SIGNAL DEVICE.

Application filed July 23, 1923. Serial No. 653,167.

To all whom it may concern:

Be it known that I, FREDERICK W. HUNT, a citizen of the United States, residing at Pasadena, in the county of Los Angeles and State of California, have invented certain new and useful Improvements in Signal Devices, of which the following is a specification, reference being had therein to the accompanying drawing.

10 The present invention relates to electric signals, and aims to provide a simple and convenient device to be attached to and carried by the arm for illuminating the hand during darkness, such as when giving signals by the hand while driving an automobile, in order that the hand can be observed by the drivers of other machines and by pedestrians; the device also being useful by ushers in theaters or by theater patrons 15 for locating seats, by messengers or delivery men for convenience in reading addresses of letters or packages in darkness, etc.

It is the object of the invention to provide a self-contained electric lamp including a 20 battery, bulb and switch to be conveniently carried by the arm, with means for attaching the lamp unit to the wrist, and means for directing the light rays toward the hand for effectively illuminating the hand.

30 Another object is the provision of a lamp unit having combined therewith a reflector of novel form for directing the light rays to the hand, and provided with a colored panel or window for attracting attention to 35 the device and for giving an effective signal in connection with the illumination of the hand.

With the foregoing and other objects in view, which will be apparent as the description 40 proceeds, the invention resides in the construction and arrangement of parts as hereinafter described and claimed, it being understood that changes can be made within the scope of what is claimed, without departing from the spirit of the invention.

The invention is illustrated in the accompanying drawing, wherein—

Figure 1 is an elevation of the device as applied to the arm.

50 Fig. 2 is a cross section on the line 2—2 of Fig. 1 showing the attaching strap and pad.

Fig. 3 is a front end view of the lamp unit with the reflector thereon, the strap and pad 55 being removed.

Fig. 4 is a longitudinal section on the line 4—4 of Fig. 1, showing the lamp unit in elevation.

In carrying out the invention, there is provided a self-contained portable electric 60 lamp including a case 7 of suitable size and shape to be conveniently applied to the arm, preferably at the back of the wrist, and a lamp bulb 8 is carried by the forward end of the case 7. The rear end 9 of the case 65 comprises a door to be opened for replacing the battery when worn out, and the case 7 carries a switch 10 for opening and closing the circuit. Any suitable lamp unit can be used, and the inner side of the case 7 is 70 preferably concaved, as at 11, so as to comfortably fit the arm.

The edge portions of the case 7 have the loops or keepers 12 for receiving a strap 13 that extends across the outer side of the 75 case 7, and said strap has a buckle 14 for fastening it around the arm at the wrist. A pad 15 of leather or other suitable material extends across the inner side of the case to bear comfortably against the arm, and 80 said pad has slots 16 at its ends through which the strap 13 extends, whereby the pad is held in place by the strap. The pad 15 is of sufficient width or area so as to bear 85 comfortably against the arm, and the strap or band 13 enables the device to be attached to the arm at any comfortable or convenient position.

In order to concentrate the light rays on the hand, a reflector 17 is provided at the 90 forward end of the case 7, it being noted that the bulb 8 is at the forward end of the case and is directed toward the hand. The reflector 17 is of suitable sheet metal and overlaps the outer side of the case 7, and has the 95 inwardly curved end portions 18 to extend around the edge portions of the case 7 at the forward end of said case, said portions 18 being spaced apart at the inner side of the case whereby the reflector opens inwardly 100 and forwardly. The light rays from the bulb 8 are therefore directed inwardly and forwardly toward the hand, in order to illuminate the hand effectively.

The reflector or shield 17 may be secured to the case 7 in any suitable manner, but is preferably detachably connected to the shell or case 7, in order that the reflector can be removed when using the lamp as a search-light or the like. Thus, as shown, the rear 110

edge portion of the reflector 17 has an outstruck corrugation 11 to spring or snap over an outstruck rib 20 provided at the forward end of the case 7, said corrugation and rib 5 extending across the outer side of the case and across the edges thereof, to the inner side of the case, whereby the reflector will maintain itself in place on the case.

The reflector or shield 17 is of C-shape in edge view, so as to overlap the outer side of the case 7 with the curved end portions of the reflector engaging across the opposite edge portions of the case, as seen in Fig. 3, leaving the case 7 unobstructed at its inner 10 side. Furthermore, the reflector can be sprung to remove it from and apply it to the case 7. The shape of the reflector also leaves it open at the inner side of the case 7, and longitudinally of said case so as to direct the light rays effectively to the back of 15 the hand.

The reflector 17 has an opening or window 21 across which is secured a panel 22, whereby such panel is illuminated by the bulb 8 25 to be readily observed and for giving an effective signal. Thus, with the device attached to the arm at the back of the wrist, when the arm is held out from an automobile in giving a signal, with the hand in the 30 position as shown in Fig. 1, the back of the hand will be illuminated so as to be readily observed from in rear of the automobile, and the panel 22 being directed rearwardly will show a colored spot to the rear, for attracting attention and to give an effective signal 35 in connection with the illumination of the hand. The panel 22 is preferably colored red to give a danger signal.

When the device is applied to the back

of the arm, the arm can be turned for giving the signal either forwardly or rearwardly, with the thumb at the top when signalling rearward and the thumb at the bottom when signalling forward. The device can also be worn on the arm for many other 45 purposes. Thus, it can be used in theaters by ushers and patrons for locating vacant seats. The device may also be used by messengers and delivery men for convenience in 50 reading the addresses on letters and packages, and for reading house numbers. The device, when worn on the left arm can also be used, in darkness, for writing, and there are many other uses to which the device can be put although it is specially intended for 55 drivers of automobiles in giving signals during the night time.

Having thus described the invention, what is claimed as new is:—

A device of the character described comprising a lamp unit including a case for holding a battery, a lamp bulb carried by the forward end of the case, and a switch carried by said case, means for attaching said case to the arm with the forward end 60 thereof projecting toward the back of the hand, and a reflector of C-shape in edge view overlapping the outer side of the case and having its curved end portions engaging 65 across the edge portions of said case without obstructing the inner side of the case, said reflector being open at the inner side of the case and at that edge opposite to the case for directing the light rays to the back 70 of the hand.

In testimony whereof I hereunto affix my signature.

FREDERICK W. HUNT.
